UNITED STATES PATENT OFFICE.

WILLIAM H. WHITE, OF ROANOKE, VIRGINIA.

SAND-TRAP.

1,117,119.

Specification of Letters Patent. Patented Nov. 10, 1914.

Application filed June 2, 1914. Serial No. 842,425.

To all whom it may concern:

Be it known that I, WILLIAM H. WHITE, a citizen of the United States, residing at Roanoke, in the county of Roanoke and 5 State of Virginia, have invented new and useful Improvements in Sand-Traps, of which the following is a specification.

The invention relates generally to an improvement in sanding devices for locomotives, and particularly to an element of such 10 devices known as the sand trap, wherein the sand is lodged by gravity from the source of supply, and from which it is forced through the feed tube to the track, the present invention constituting an improvement 15 upon that shown in my prior Patent No. 1,086,964, dated Feb. 10, 1914.

The main object of the present invention is the provision of a sand trap in which the 20 use of a nozzle having a check-valve or other elements liable to be choked with sand is avoided, and in which a self-clearing nozzle of novel construction is employed.

A further object of the invention is the 25 provision of a trap in which the sand channel is so formed as to prevent the gravity feed of the sand therethrough, while at the same time affording little obstruction to the movement of the sand under the influence of 30 the air blast.

A further object of the invention is the 35 provision of a nozzle which, in addition to being self-clearing, may be removed to permit the trap to be cleaned out, and which is designed to direct the air blast in such a manner as to secure a positive feed of the sand, while avoiding an objectionable concentration and wearing action of the blast on the walls of the trap.

40 A further object of the invention is the utilization of an air blast operating through a portion of the trap and beyond the sand channel therein, which blast is utilized when necessary as a cleanout medium for the feed tube beyond the trap, whereby said tube may be at all times maintained in effective condition for the proper movement of the sand therethrough in sanding the track.

A further object of the invention is to 45 provide a construction of cleanout connections whereby proper cleanout actions of the feed tubes at the opposite sides of a locomotive may be obtained without the use of valves and also without waste of air.

55 The invention in the preferred form of details, will be described in the following

specification reference being had particularly to the accompanying drawings, in which:—

Figure 1 is a plan view of traps arranged 50 at the opposite sides of a locomotive and the coacting clean out blast delivery pipes. Fig. 2 is a side elevation of the improved trap and connections. Fig. 3 is a longitudinal section of the same. Fig. 4 is a detail section of the coupling member on an enlarged 55 scale.

The improved trap, which aside from the details hereinafter described may be in any form, preferably comprises a T-shaped body 70 1 having an upright section 2 designed for connection to a suitable pipe leading from the source of supply, and a lateral section 3, the terminal of which is designed to be connected in any usual or preferred manner to 75 the sanding or delivery tube 4 for the delivery of the material to the track. The body is interiorly and longitudinally cored to provide what I term a sand channel 5, the formed wall of this channel from a point 80 beyond the upright of the body to a point a slight distance from the outlet end of the body being on a downwardly curved plane, as at 6, the curved portion of the channel forming a trap to prevent the travel of the sand through the channel by gravity or under the jars to which the body is subjected 85 in the travel of the engine. The body 1 at approximately the juncture of the upright and lateral portions of the channel is cored 90 and interiorly threaded at 7, and above the bore or opening 7 the upright portion 2 is provided with an interiorly threaded opening 8. These openings 7 and 8 are designed to provide a means whereby the sand channel may be cleaned out by any suitable tools, when such may become necessary, the opening 7 also serving for the reception of the blast nozzle, while the opening 8 may be closed in practice by a plug or other suitable 95 closure.

The blast nozzle 9 comprises a cylindrical body having at its inner end an angular head or flange 10 for the application of a wrench, and provided at such end with a threaded nipple 11 fitting within the threaded bore 7, said nipple terminating in a reduced blast tube 12. The outer end of the nozzle is cored and internally threaded, as at 13, to receive the threaded body 14 of a coupling member 15, said coupling member being provided at its outer end with a

angular head 16 for the application of a wrench. The threads of the core 13 terminate in rear of the inner end of the core, which is flared or beveled to provide a bowl-shaped air chamber 17, centrally communicating with a blast bore or passage 18 extending axially through the body and nipple of the nozzle, said bore being flared or enlarged at its forward or delivery end and 13 communicating with the bore 19 of the blast tube 12.

As shown, the blast tube 12 extends into the trap at a slight upward angle of inclination, thereby directing the sand practically longitudinally of the channel, and thus avoiding to a material extent the usual cutting of the trap body by the sand. The air blast is delivered through the coupling member 14 from a supply pipe 20 connected therewith to supply air to the receiving chamber 17, in which it slightly expands, and from which chamber it passes to and through the bore 18, and finally from said bore into and through the bore 19 of the blast tube 12, from which it issues into the channel 5, thereby feeding the sand with a required pressure into the sanding or delivery tube 4. By making the bores or passages 19 and 18 of increased diameter, one 30 with respect to the other, the air is permitted to expand to a determined extent, and with a proper volume and pressure proportioned to the diameter of the channel 5 to avoid objectionable concentration of the blast and delivery of the sand in an objectionably compact mass and under objectionable pressure. Hence the sand will be delivered in a fairly spread body under a comparatively few, but at the same time 40 sufficient pressure for delivery, so that the concentration of the blast and cutting away of the walls of the trap or delivery tube will be effectually avoided. A trap embodying my construction is therefore adapted for long and continuous service.

It will be observed that the nozzle 9 is devoid of check valves or other elements liable to clog and render the nozzle inoperative, the constricted diameter of the bore 18 tending to prevent the passage of particles of sand thereinto, while the bore 19 of the blast tube 12 is of sufficient diameter to be self-clearing under all ordinary and normal conditions. It sometimes happens, however, 55 that small particles of sand will work back into the bore 18 from the jars and vibrations incident to the travel of the engine, and the chamber 17 is therefore provided to receive and trap these particles, as well as to serve as an air expansion chamber. To effect the dislodgment of these particles and a self-clearing action of the nozzle, whereby it is at all times maintained in operative condition, the threaded portion 11 of the coupling member 13 is formed to provide a

blast rose or induction nozzle 21 having an annular series of jet orifices 22. These orifices extend from the bore of said coupling member to the chamber 17, which is of relatively greater diameter than said bore, at 70 an outward angle of inclination, whereby currents of air issuing from the jet orifices are adapted to strike the curved wall of the bowl and produce a whirl or vortex, whereby the entrapped sand is taken out by the whirling column of air and carried therewith through the bores 18 and 19 into the channel 4. Any retention of sand particles by gravity in the chamber 17 is thus prevented and the nozzle kept clear without the use of 80 valves or other extraneous devices which are liable to bind, clog or to be otherwise rendered inoperative by particles of sand.

Upon removing the nozzle from the opening 7 the channel may be cleaned out through 85 said opening, as will be readily understood. An auxiliary pressure channel 23 is formed in the body 1 and opens into the delivery end thereof beyond the delivery end of the sand channel 4, said pressure channel entering the body at a point adjacent its forward end, the entrance end 24 being internally threaded to receive the delivery end of a blast pipe 25, while the outlet 26 of said passage is internally threaded to receive the 90 inlet end of a clearance blast tube 27 which extends into the entrance end of the sanding or delivery tube 5. The tube 5 curves downwardly at its entrance end to dispose said tube at the proper delivery angle, and the tube 27 is similarly bent within the tube 5, so as to lie out of the path of the sand delivered into said tube 5 by the blast nozzle. Through the channel 23 and tube 27 a blast of air may be delivered into the 105 tube 5 to free said tube 5, whenever choked, from accumulated material, as will be readily understood. The auxiliary blast pipes 25 extend up to the top of the boiler and are there connected by a T-coupling 28 with a supply pipe 29 leading from the locomotive cab, said pipe 29 having a controlling valve 30, whereby the feed of air to said auxiliary channels may be controlled. The 110 channels 23 are longitudinally tapered, being 115 of restricted diameter at their delivery ends with relation to their entrance ends and to the pipes or tubes 5, so that the blast of air jetting therethrough is retarded to a degree in its flow. By thus constricting said channels the necessity of employing valves to control the supply of air from the pipe 29 to the respective channels 23 is avoided, since, in the event of one of the tubes 4 being clogged and the valve 30 being opened to supply air through the channels 23 of both sanding tubes 5, the air delivered into the free or clear sanding tube will be so restricted in its flow as to insure the delivery 120 of a clearance blast to the clogged tube, 125 130

whereby the latter will be cleared. This construction prevents the delivery of air solely through the course of least resistance, by which the clogged tube would be deprived of a blast, and also avoids the addition of valves or other controlling devices increasing the susceptibility of the sanding apparatus to derangement.

It will be seen from the foregoing that the present invention provides substantial improvements over my prior patented structure and obviates the necessity of employing a shelf overhanging the delivery end of the nozzle and clearance channel or pocket beneath the delivery end of the nozzle, also the use of a check valve in the nozzle, while at the same time a free cleaning out of the sand channel whenever required may be conveniently effected. It will, of course, be understood that the nozzle may be mounted and locked for adjustment to dispose the delivery end of the nozzle to regulate the feeding effect of the blast on the sand, as in my aforesaid patented structure.

25 I claim:—

1. A sand trap formed with a sand channel, a blast pipe connected therewith, and a blast nozzle communicating with said channel, said nozzle having a longitudinally continuous bore provided with a chamber for collecting particles of sand working therein and means for delivering the blast in a plurality of jets in said chamber at an angle to the line of the bore so as to produce a whirl in the current of air to take up and discharge said particles.

2. A sand trap formed with a sand channel, a blast pipe connected at an angle therewith, a clean-out blast channel closed against the sand channel, and a blast tube leading from said blast channel and extending into said blast pipe at an angle conforming to the latter.

3. A sand trap formed with a sand channel, a blast pipe connected at an angle therewith, a clean-out blast channel closed against the sand channel, said blast channel having an enlarged receiving end and a relatively constricted delivery end, and a blast tube leading from the constricted delivery end of the blast channel into said blast pipe at an angle conforming to the latter.

4. In a sanding apparatus, the combination of a pair of sand traps each having a sand channel and a constricted blast channel closed to said sand channel, blast pipes connected with the delivery ends of the sand channels of the traps, blast tubes leading from the delivery ends of the blast channels into the blast pipes, air conducting pipes leading to the inlet ends of the blast channels, a cross pipe connected with said conducting pipes and an air supply pipe connected with said cross pipe.

5. A sand trap formed with a sand channel and a blast nozzle having a delivery end opening into said channel, and a blast channel provided with a sand collection chamber, and means for producing a whirl in the line of the blast to clear said chamber and channel.

6. A sand trap formed with a sand channel, and a blast nozzle having a blast channel provided with receiving and delivery portions of relatively increasing diameters and an enlarged air receiving and sand collection chamber communicating with the inlet end of the receiving portion of the channel, and means for supplying a blast to said channel and producing a whirl in the blast to clear said chamber and channel.

7. A sand trap having a sand channel, and a blast nozzle extending into said channel and provided with a bore having relatively constricted and enlarged receiving and delivery portions, and means for collecting particles of sand working into said restricted portion of the bore and producing a whirl current of air to take up and discharge said particles.

8. A sand trap having a blast channel, a nozzle having a bore formed with an enlarged bowl-shaped chamber at its receiving end, and a blast pipe coupling connected with said nozzle and having orifices arranged to deliver the blast at an angle to the line of the bore against the curved wall of said chamber.

In testimony whereof I affix my signature in presence of two witnesses.
